B. S. Myers,

Wheel Cultivator.

No. 28,370.

Patented Jan. 18, 1870.

Benjamin Steffes

UNITED STATES PATENT OFFICE.

BENJAMIN S. HYERS, OF PEKIN, ILLINOIS.

IMPROVEMENT IN CULTIVATORS.

Specification forming part of Letters Patent No. 98,970, dated January 18, 1870.

To all whom it may concern:

Be it known that I, B. S. HYERS, of Pekin, in the county of Tazewell and State of Illinois, have invented certain new and useful Improvements in Cultivators; and I do hereby declare that the following is a full and exact description thereof, reference being had to the accompanying drawings, forming part of this specification, and to the letters of reference marked thereon.

My invention relates to that class of implements known by agriculturists as the "wheel-cultivator;" and its objects are to construct and arrange the plows of the cultivator to the frame and connecting the draft in such a manner as to cause the whole to make it easy both for the team and operator to work the same, as every part readily adjusts itself to the motion of the horses, and the attachment of the beams of the plows to the axles or frame can be so adjusted as to regulate the gage of depth of the plows, and also the line of draft in the different kinds of soil, at the same time they can be made to conform to all the sinuosities of the rows.

The nature of this invention consists in providing a straight wrought-iron axle, in combination with the wheels and frame for each wheel, each axle being independent of the other, and each supporting the respective sides of the frame.

It also consists in the use of cast-iron or other suitable supports or clamps made in longitudinal sections and of peculiar and novel form, in combination with curved or other properly-formed wrought or cast iron braces or supports, clamped together with the other mentioned cast-iron supports around each axle, for the purpose of its ready detachment and to support the frame.

It further consists in the employment of two adjustable laterally-inclined braces, in combination with the before-mentioned clamps and tongue, to prevent any lateral movement or spreading of the frame when the plows are set to throw the soil toward the plants, and to elevate or lower the inner ends of the axles, as may be desired, for the purpose of taking up the slack in the clevises and joints in the working portions of the machine.

Another feature of my invention is that I make a direct attachment of the beams of the plows to the whiffletrees forward of the wheels,

through the medium of clevises and rods arranged in such a manner as to receive the support of the frame through the medium of the tongue; also, for the further purpose of regulating the draft or pressure on the horses' necks by means of an adjustment provided for this purpose.

It also consists in fitting the clevis on the inner end of the axle and providing the same with two or more notches, in combination with a sliding socket, so that the distance of the plows from each other may be changed to accommodate them to the width of the rows, as will be more fully explained; also, a sliding piece made to move on the axle and within the clevis, which is provided with three or more holes for the purpose of attaching the plows to the same, so that they may be moved or changed on this as well as on the axles, thereby securing a wide range for the plows sufficient to add another plow; also, the combination of a sliding piece on the axle with the clevis, each provided with corresponding holes, so that a pin may be inserted for the purpose of making the plows rigid to the frame, and to prevent the plows taking a sinuous course when the soil is light and the rows straight, and for the purpose of avoiding the necessity of holding the same by hand.

To enable others skilled in the art to make and use my invention, I will proceed to describe its construction and operation.

Figure I is a top plan view of my improved cultivator. Fig. II is a longitudinal sectional elevation of the same, taken from the line XX.

Letters of like name and kind indicate like parts in each of the figures.

A and A' represent two wheels, which may be of wood or iron of common construction and of suitable dimensions, that run on independent and separate axle B and B', upon which are clamped cast or wrought iron straps C C', extending upward to a proper distance, and to these said straps are bolted curved braces D D D D, upon the top and at the outer end of which are secured, by bolts or other means, two cross-bars, E E, and to these is secured the pole or tongue F, by which the machine is guided while being operated. These parts now described constitute the frame of my cultivator, which is carried and supported on the wheels A A' and axles B B'. G and G' represent the cultivator or plow

beams, of suitable dimensions to carry and support the plows *aa aa*, secured to the standards *e e*, the latter of which are secured by means of pivot-bolts to the beams *G G'*, so as to allow them to be adjusted to any desired inclination, and are held rigidly in their position by means of braces *oo oo*, on which are screw-nuts and following nuts to hold the said standards in position.

S S are laterally-inclined braces, the lower ends of which are connected to the upper portion or ends of the clamps *C C'*, and the other ends are secured underneath the tongue in such a manner as to allow them to be elevated and lowered, so as to set the tread of the wheels out or in, as may be desired, and to prevent the wheels from spreading apart when in operation.

On the forward end of the beams *G G'* are clevises *H H*, the front ends of which are made broad, so as to admit of several holes being made therein for the purpose of changing the line of draft, or to allow other pins to be inserted to make the beam rigid to the axle when the soil is light and the rows straight, under which circumstances this can be done, at the same time avoiding the necessity of the operator guiding the plows by the handles *II*, which are secured to the rear end of the beams.

J J are sliding or movable lugs, the rear ends of which are made to exactly correspond and fit in the clevises *H H*. These lugs are made to move laterally with the line of draft, so as to throw the plows farther apart when desired. The rear ends of these lugs are elevated, so as to cause the plows to run shallower, and if found to run too deep they can be reversed or turned upside down, which will materially change the running of the plows. The position of these lugs will be governed by the nature of the soil.

K is a sort of double-tree, secured or attached to the under side of the tongue by means of staples or other device.

L L are pendent bars or rods, attached to each end of the said double-tree by means of staples and hooks or other suitable means.

M M are cockeyes fitted on each axle, which stride the movable lugs before described. At the front end of each of the cockeyes are rods or links *W W*, that connect with the pendent bars or rods *L L*; also, to these pendent bars are connected other rods, *N N*, that extend forward and connect with the bow *O*, the latter of which is connected to the under side of the tongue. The front ends of the rods *N N* are provided with hooks that pass through

rings, which are secured to the outer ends of the bow *O*. These hooks are for the purpose of hitching the team to the cultivator when in operation.

P P are hooks secured to the rear ends of the plow-beams for the purpose of elevating the plows and engaging the hooks in the elevises, stirrups, rings, or other devices, *Q Q*, when it is desired to move the cultivator from place to place.

The operation is simple, easy, and effective, consisting in attaching the team to the rods *N N*, the plows being adjusted according to the nature of the soil and the work to be done.

When it is desired to move the cultivator from place to place, the rear ends of the plow-beams can be raised and secured in an elevated position by means of hooks provided for that purpose.

When the line of draft of the plows is required to be changed, the clevis can be moved to one of the outer holes in the lug, thus changing the line of draft, as desired, and when the plows are required to be set farther apart the plows and lug can be elevated, so as to allow the projection or lug in the cockeye to pass by the notch in the sliding lug, and when they are lowered they must retain their position.

Having thus described my invention, what I claim as new, and desire to secure by Letters Patent of the United States, is—

1. The two straight axles *B B'*, independent of each other, in combination with the straps *C C'*, substantially as herein shown and described, and for the purposes set forth.

2. The two adjustable laterally-inclined braces *S S*, in combination with the straps or clamps *C C'* and tongue *F*, substantially as shown and described, and for the purposes set forth.

3. The sliding lug *J*, within the cockeye *M*, provided with one or more notches, so as to allow it to pass by the clevis *H*, substantially as herein shown and described.

4. The cockeye *M*, in combination with the sliding lug *J* and rod or link *W*, substantially as and for the purposes set forth.

5. The combination and arrangement of the clevis *H* and sliding lug *J*, provided with holes for pins or bolts, so as to make the plows rigid to the line of draft, substantially as herein shown and described.

BENJAMIN S. HYERS.
